United States Patent Office.

WILLIAM SANGSTER AND JOHN BRETZ, OF SPRINGFIELD, ILLINOIS.

Letters Patent No. 82,037, dated September 8, 1868.

IMPROVED BRICK-MOULD.

The Schedule referred to in these Letters Patent and making part of the same.

Be it known that we, WILLIAM SANGSTER and JOHN BRETZ, both of Springfield, county of Sangamon, and State of Illinois, have invented a new and useful Machine for Moulding Brick; and we do hereby declare that the following is a full, clear, and exact description of the construction and operation of the same, reference being had to the accompanying drawings, and to the letters of reference marked thereon.

Figure 1 represents the mould-box A, with the partition-framework B of fig. 3, fitted in it ready for use.

Figure 2 represents a section of the mould-box A, showing the slots or grooves in which the partitions C C of the partition-framework B slide up and down.

Figure 3 represents the partition-framework B separate and distinct from the slotted mould-box A.

Figure 4 represents a cross-section, showing the way in which the partitions C are loosely united to the partition-framework B.

The outer frame of the partition-framework B is made of iron, and the partitions C can be made either of metal or wood. The end-pieces are made of thin metal or wood.

D D are cross-bars of iron, to which the partitions C C are attached and connected with the framework B, to which they are loosely riveted, so that in drawing the framework up, they will draw straight with the grooves if the workman should incline the framework one way or the other.

E are the handles, by which the partition-framework is lifted.

F F are the catches on each end of the mould-box A, upon which the thumb of the workman rests when raising the partition-framework B, and by which the whole machine is raised from the soft brick underneath, when the handles of the partition-framework are raised to a level with them.

The operation of the machine is as follows: The whole machine, as represented in fig. 1, is turned over and filled with clay as in all moulds, then it is returned to the position occupied in fig. 1. The workman then places his thumbs upon the top of the catches F, and his four fingers underneath the handles E. With his thumbs he presses the mould-box down, and with his fingers he raises the partition-framework up sufficiently high to loosen the soft brick, and until the handles E E come up on a level with the bottom of the catches F F, when the fingers slide under the catches, and the whole machine is raised off from the soft brick underneath. The partitions C C being loosely riveted, so that they will swing easily either way, cannot be drawn up out of a perpendicular by any inclination of the framework B, so that the danger of misshaping any of the soft brick is thus obviated.

The partition-framework B being separate from the slotted mould-box A, the two can be washed much easier.

The partitions C C differ in their construction from partitions in other moulds, from the fact that these are movable and others are immovable.

What we claim as our invention, and desire to secure by Letters Patent, is—

The combination of the frame-bars B with the bars D pivoted thereto, supporting the partitions C, with the slotted mould-box A, handles E, and ledges F, all constructed in the manner described, and for the purposes set forth.

WILLIAM SANGSTER,
JOHN BRETZ.
